ELECTRICAL SIGNALING SYSTEM

Eric Bertram Ireland, Liverpool, and Eric Wyn Jones, Nottingham, England, assignors to Associated Telephone & Telegraph Company, Chicago, Ill., a corporation of Delaware

Application September 16, 1939, Serial No. 295,176
In Great Britain September 17, 1938

11 Claims. (Cl. 177—367)

The present invention relates to electrical signaling systems and is more particularly concerned with systems for transmitting fire alarm signals to a central station from a plurality of boxes located at different points all of which will usually be accessible to the public.

The invention has particular application to fire alarm systems of the closed circuit type in which a plurality of boxes are series connected in a loop circuit over which a current normally flows. With this arrangement a calling street box is arranged to transmit a series of impulses indicative of its code number to the central station where an indication of the number is given and to improve the reliability of the system it is usually arranged that the box is earthed during sending and the loop is interrupted according to the appropriate code on both sides of the earth connection.

The general object of the invention is to provide improved arrangements whereby calls from short-circuited fire alarm boxes shall be satisfactorily handled with the minimum of interference with the normal working of the system.

According to one feature of the invention in a fire alarm system of the closed circuit type arranged so that when a box is pulled interruptions in a loop circuit and also intermittent connections to earth are produced, the code from a short-circuited box is satisfactorily received by arranging that when earth is intermittently applied to the circuit without the loop being interrupted, the connections are automatically altered so that the code represented by the intermittent earth connections produces operation of the code responding equipment.

According to another feature of the invention, in a fire alarm system of the closed circuit type arranged so that when a box is pulled interruptions in the loop circuit and also intermittent connections to earth are produced, as soon as a box is pulled earth is connected to the loop and serves to initiate a test whereby conditions are established such that if the loop is not satisfactorily opened when the earth connection is removed, the circuits of the code responding equipment are altered so that the code represented by the intermittent earth connections produces operation of the responding equipment.

A further feature of the invention in a fire alarm system of the closed circuit type arranged so that when a box is pulled interruptions in the loop circuit and also intermittent connections to earth are produced, as soon as a box is pulled

earth is connected to the loop and serves to initiate a test whereby conditions are established such that if the loop is not satisfactorily opened when the earth connection is removed, a device responsive to the intermittent earth connections is enabled to produce corresponding interruptions of the loop so as to operate the code responding equipment.

The invention will be better understood from the following description of two methods of carrying it into effect which should be taken in conjunction with the drawings comprising Figs. 1-3. Of these Figs. 1 and 2 when arranged side by side with Fig. 1 on the left show the invention applied to a system employing boxes of the non-interfering succession type while Fig. 3 shows the invention applied to a system using boxes of the plain coding sector type.

Considering the circuit operation of Figs. 1 and 2, the general operation in response to a normal fire call with all boxes in order will first be dealt with. Assuming that fire alarm box FA, Fig. 1, is calling, the code wheel begins to rotate in a clockwise direction, as shown, driving the off-normal cam in a counter-clockwise direction. These cams are arranged to operate the off-normal contacts N1 and N2 a short interval before the first operation of the impulse contacts IMP¹ and IMP², thereby to provide an initial test period. During this period earth via rectifier MRA is therefore connected over contact N1 to both conductors of the first alarm loop. The high resistance earth test relay E thereupon operates and at armature e1 operates relay ER. Relay ER locks over its other winding to positive over armatures er1, er2, gr3 and da1 and also at armature er2 short circuits relay E so as to provide a holding earth for the box succession coils B1 or B2 and B3 under short-circuited box conditions via the winding of the low resistance relay EX. Relay EX now operates and thereupon energises relay EB, Fig. 2, which brings up relay EC and this relay in turn operates relay ED at armature ec1. Relay EC also at armature ec2 reverses the polarity of the earth test circuit by connecting earth over relay ET to the opposite pole of the loop battery BA. Relays E and EX are thereby disconnected, so that relay EX releases at about the same time as relay ED is operated. Since earth is connected to the loop over the rectifier MRA at the calling box, relay ET will be unable to operate under this condition since the rectifier will not be conductive. To improve the operating conditions for relay ET in case a faulty

earth exists on the loop relay EC at armatures *ec3* and *ec4* short-circuits the relays T, RA, and RS in the A leg and inserts relay RB in the B leg.

With regard to the function of relays T, RA and RS it should be explained that with the normal loop current of say 50 milli-amps, these relays are held operated, the punch register PR and gong GG also being energised under this condition. The current is indicated by the milliammeter MA and may be adjusted by the variable resistance VR. The initiation of a telephone call from a street box causes a resistance to be inserted in the loop which reduces the loop current to say 30 milli-amps whereupon relay T releases and operates relay TA as will be described subsequently, the remaining series equipment still being held by this current. Relays RA and RB, the register PR and gong GG have all approximately the same operating and releasing values and will operate with a current of the order of 25 milli-amps and release with a current of 11 milli-amps and under normal conditions they will respond satisfactorily to code impulses. Under conditions where a box is shunted by a leak resistance as sometimes occurs, the loop current will not drop to zero each time the box impulse springs open and conditions may arise where the relays and puncher will receive sufficient current during the break periods to prevent their efficient response. To safeguard the system from unreliable operation from this cause an additional supervisory relay RS is provided which will only release if the loop current falls to less than say 5 milli-amps. If this relay remains operated when the first break is delivered from the box, short-circuited box working using earth return is immediately brought into operation so that the complete code transmitted is correctly received. On the other hand if this relay releases, ordinary loop working will be retained since under this condition the loop current flow during break periods will clearly be so small as not to interfere with the proper operation of relay RA and the puncher and gong. Although relay RB is shown on the drawing it is not concerned with the operations involved in carrying out the present invention and only performs a useful function under earthed line break conditions.

Continuing the description of normal operation from the point when relay EC operated during the initial test period of the calling box, relay EX will be released as pointed out previously and relays EB and EC will release in turn. Relay EB thereupon completes an operating circuit for the slow-to-operate relay EF while the release of relay EC reconnects relays E and EX on to the loop. However since relay E is still short-circuited owing to the locking of relay ER, relay EX only will immediately operate and during the slow release period of relay ED which commences to fall away on the release of relay EC, relay EWS will be operated. Relay EWS locks up at armature *ews1* over its second winding and at armature *ews2* opens the circuit of the slow-to-operate relay EF before it has had time to operate.

If, however, the operations described are initiated by a fault earth on the line rather than by the pulling of a box, relay ET will operate when the battery polarity on the line is reversed. Relay ET thereupon at armature *et1*, removes the short-circuit from across relay ETR and so

causes it to energise and lock up at armature *etr1* in series with relay EC. The latter relay thus remains held when relays EX and EB release so that no circuit is re-completed for relay EX and relay EWS cannot be operated over armatures *etr1* and *etr2* as in the normal case. Consequently relay EF operates shortly after the release of relay EB and at armature *ef2* lights the earth fault alarm lamp EAL, at armature *ef1* releases relays ETR and EC and at armature *ef3* removes the short circuit from relay E so that on the release of relay EC relay E is again introduced into the earth test circuit. Relay E re-operates and ensures the maintenance of relays ER and EF so that the earth alarm persists so long as the fault remains.

Continuing the description of a bona-fide call, no further operation ensues until the fire alarm box transmits the first break impulse of the train or trains constituting the box code and relay EX will then release and also the loop circuit relays T, RA and RS. The release of relay RS indicates that no short-circuit exists on the box so that no circuit is completed to the short-circuited box working relay SC and the call is received at the central station over the loop in the normal manner. Relay P responds to impulses delivered from relay RA at armature *rat* and repeats them to the indicator circuit IC while the received code is punched on the tape by the register PR and sounded on the gong GG. Relay RS in responding to the code impulses operates relay GR over armatures *rs1* and *ps1* and this relay holds during pulsing due to its slug. When it operates, it releases relays ER and EWS by disconnecting the holding earth thereto at armature *gr3* and the earth circuit relays EX, E and ET are disconnected at armature *gr2*.

It will be understood that the armature of the fire alarm box is made slow-to-release in order that the box will hold in when relay EC is momentarily operated during the earth discrimination test and removes the holding earth for the calling box earth succession coil.

Assuming now that there is a short-circuit on the box, the circuit operation at the central station up to the reception of the first break will be the same as already described in connection with a normal call. In this case, however, owing to the short-circuit, relay RS will not release on the first break and a circuit will be completed for relay SC, which operates over its lower winding and at armature *sc1* locks up by way of its upper winding. Relay SC also at armature *sc2* changes over the loop circuit to earth return working, the two sides of the loop being connected in parallel over armature *sc6* and resistance YA. Hence since the box impulse springs are broken at this moment relay RA, the gong GG and the register PR will release; relays T and RS also releases but these relays are not concerned in the present operation. Succeeding impulses are received by relay RA and the register over the earth return circuit and all codes transmitted from the short-circuited box are thus received without loss at the central station equipment. Relay SD is operated from relay SC and locks to the key KSCR and lights the short-circuited box lamp SBL over armature *sd2*.

On the completion of the code transmission from the calling box, the off normal springs N1 and N2 will restore and since earth working is in progress the line circuit relays will release. Relay P will therefore remain operated and main-

tain relay G which completes an energising circuit for the slow-to-operate delay relay DA. It will be understood that although this relay previously received impulses during the coding-in it would not operate. During reception of the call relay GR was operated and due to its slug remained energised and therefore released relays ER and EWS as pointed out above. On the operation of relay DA after a period of the order of six seconds, relay SC is released and in turn opens the circuit of relay SCA which was operated when relay SC originally operated. The function of relay SCA is to prevent relay DA operating relay EW and so bringing about full "line break" earth working on the fire alarm loop which differs from "short-circuited box" earth working in a manner to be described. Relay SC on releasing restores the circuit to loop working, whereupon the line relays operate and release relay P which in turn disconnects relay DA. Due to its slug, relay SCA holds during this time and prevents earth being extended over armatures da_1 , sc_1 and g_1 to operate relay EW. When the maintenance officer at the fire station subsequently operates the short-circuit call release key KSCR, relay SD will be released at key contacts KSCR1 to extinguish the short-circuited box call indication lamp SBL.

The "short-circuited box" earth working as described above which is employed when a call is received from a short-circuited box differs slightly from full earth working, this difference being mainly intended to give improved possibilities of succession working if a good box should call when a box shunted by a fairly high resistance is already coding-in. Under full earth working conditions, which are brought into effect in the case of a line break, relay EW is operated over armatures da_1 and g_1 after the slow period of relay DA. If a call is subsequently received either relay SA or relay SB (not shown) is operated in addition depending on whether the call is originated on the A or B leg. If the call is originated on the A leg, relay SA is operated to disconnect the B leg at armature sa_1 and similarly for relay SB. By this means a second call originated simultaneously with the first and on the opposite leg is prevented from sending in its code and so spoiling the code already being received from the first box. If, however, one leg were disconnected for short-circuited box working as in the full earth working condition, it might not be possible for a second good box calling on the same leg as the first to hold the line relays operated in series with the resistance across the faulty box already coding and thus restores the loop working condition for succession working. It will be understood that if the line relays failed to remain operated due to the high value of the resistance across the faulty first box, the second good box would fall out but would maintain a continuous earth via its rectifier on to the line and would thus tend to interfere with the response of the line relays to the earth pulses being transmitted from the faulty box already coding. With the short-circuited box working shown however, both legs of the loop are kept intact and succession working between a second good box calling and an already running box having a fairly high resistance shunt thereon can readily be effected, since when the second box calls with the first box already running, the earth extended from the second box will immediately hold the line relays operated round the other side of the loop

and so bring in loop working in the manner to be now described.

When a call is being received from a short-circuited box and another call is originated at a good box in the loop, the second box on running on its test tooth will extend continuous earth via its rectifier on to the loop for such a time as will hold the line relays long enough to allow relay GR to release, this relay normally receiving a pulse over armatures p_1 and rs_1 each time relay RS restores due to the pulsing from the first box. Relay GR thereupon operates relay SE over armatures gr_1 and sc_5 and this relay at armature se_2 releases relay SC to allow ordinary loop line conditions to be restored. At armature se_3 any possibility of short-circuiting the high resistance relay E in the earth test circuit is prevented so that the short-circuited box will be unable to hold operated over its earthed succession coil and will fall out unless the resistance leak across the box is such as will allow sufficient loop current to flow through the loop succession coils to hold them in which case the first break delivered by the second box will release the short-circuited box. When the shorted box falls out, the second good box carries on coding-in. During this time relay GR will be again operated and releases relay SE which again prepares a locking circuit for relay SC. After coding from the second box has been fully received the release of relay GR causes earth to be re-applied to the earth circuit relays E and EX and the short-circuited box will again bring up relay SC in the usual manner and will recommence to send in its code.

Considering now the case of a telephone call from a short-circuited box, the normal momentary increase of resistance in the loop circuit will be clearly ineffective owing to the short-circuit on the box, but at the same time earth over the box rectifier is momentarily connected to the line. It should be explained that in the case of a telephone call from a short-circuited fire alarm box the connection of the rectifier earth to the line would be effected manually by the fire or police officer initiating the call while in the case of a call from an ambulance telephone box situated in the same loop as the fire alarm boxes this would be automatically effected, for instance in the manner described in British specification No. 471,759. The momentary connection of the rectifier earth to the line causes relay SC to be operated in the manner already described and this relay in turn operates relays SD and TA to display short-circuited box and telephone calls on the indicator panel by lighting the lamps SBL and TCL respectively. The operation of relay SC initiates short-circuited box working conditions and when the rectifier earth connection at the box is removed, the line relays will release and bring up relay P which in turn operates relay G which completes a circuit to the delay relay DA. Relay DA on operating after its slow period operates relay EW over its left-hand winding to bring about the changeover to earth working so as to provide feeding current to the telephone instrument, not shown, at the calling box. Relay SD also at armature sd_3 disconnects one winding of the repeating coil RPC, which connects over leads 12 and 13 with the station telephone circuit, so that when the telephone key KTS is operated, speech may take place under this condition. Clear down is subsequently effected by operating the short-circuited box release key KSCR, whereupon at contacts KSCR1 relay SD is released and at contacts KSCR2 relay EW is released. Relay

TA is released at contacts KTS3 on the operation of the telephone key.

It will be noted that in the case of a fire call from a short-circuited box, relay TA is operated but it will be understood that relay CO associated with the indicator circuit is operated over contacts *ic* when a full code has been received and so at armature *col* disconnects relay TA. A telephone call indication will not therefore appear under this condition.

In case due to a box fault the rectifier earth therein is permanently connected to the alarm loop, an ordinary call will be simulated initially in response to which relay EWS will be operated and will lock. At armature *ews5* an operating circuit is completed for the slow relay DA and since relay EWS is not released by the operation of relay GR after the predetermined period relay DA operates and at armature *da1* lights the so-called box earth lamp BEL. Relay DA also at armature *da1* releases relay EWS and this relay thereupon extinguishes the lamp BEL and disconnects the circuit to relay DA so that the cycle of operations repeats itself and causes the lamp to flash. In actual practice it might be more convenient to prevent the earth test circuit from being continually broken down and set up again as in the circuit shown by arranging that relays DA and EWS, on operating together bring up a relay which locks and maintains either a continuous or intermittent circuit for the lamp BEL.

The armature *co2* in the circuit of relay DA is to prevent this relay being brought in when during succession working one or more boxes fall out while another box is coding in. During this time it will be appreciated that a rectifier earth is maintained on the loop and it may be maintained long enough to allow relay DA to operate if the circuit to this relay is not broken by relay CO which is operated when a full code has been received at the central station.

Referring now to Fig. 3 this simply shows the essential equipment required for handling short-circuited box calls on straightforward sector box, i. e., non-succession working systems. On a normal call from a good box, relays RA, RB and T release in accordance with the operation of the impulsive springs and the punch register PR and gong GG are operated in the usual manner. Relays PA and RB operate slow relay RA whereby the earth test relay E is disconnected at armature *pa2* and does not produce any effect on the auxiliary equipment.

If the calling box is short-circuited however relay E operates by way of the earth at the box when a call is initiated and at armature *et1* completes a circuit for relay ER which in turn pulls up relay J which locks over its lower winding. Relay J at armature *j2* completes a circuit for the time delay relay EA which is utilised to bring in an earth alarm indication after a period of the order of twelve seconds as will be described subsequently. Relay ER at armature *er2* operates relay M of the counting relays and this relay in turn prepares a circuit for relay N which at this stage is short-circuited by the positive potential extended from armature *et3*. It is assumed that three-digit box codes are to be catered for and on the transmission of the hundreds digit, relay E responds to the impulses but relay ER due to its slug holds operated during this time. It will be appreciated that due to the short-circuit on the box relays RA, RB and T are unable to release so that relay PA is not operated. During the interdigital pause the impulsive springs

at the box remain open so that relay E releases and during this time relay ER will in turn release and remove the short-circuit from relay N which operates in series with relay M which holds energised in this circuit. On the transmission of the tens digit, relay E pulses and again operates relay ER which operates relay P and this relay in turn prepares a circuit for relay Q which at this time is short-circuited. In the interdigital pause following the tens digit, relay Q operates in series with relay P which remains held and after the reception of the units digit relays R and S will be operated in a similar manner. The operation of all the relays M—S indicates that a bona-fide call from a short-circuited box is in fact being received, and relay S at armature *s1* prepares a circuit for the short-circuited box working relay SX.

It will be understood that each street box in 20 running down makes a total of three transmissions of its box number and hence when the first make impulse of the hundreds digit is transmitted on the second round, relay E is again operated and brings up relay ER once more so that 25 relay SX is operated and locks up over its lower winding. On the first break impulse, relay E releases and now operates relay EP since a circuit is completed for it over armatures *et1* and *sx5* and this relay thereupon breaks the loop circuit at armature *ep1* and thus repeats the 30 pulses on to the line relays and punch register. Relay PA now operates but in this case the circuit for relay E is maintained over armature *sx4*. Relay PA also at armature *pa1* disconnects any 35 further operating circuit for relay SX though this operation serves no useful function in the present circumstances. When the code wheel reaches the second make of the hundreds digit, earth is re-applied to the line and relay E re-operates since although relay EP is operated at this time to disconnect the loop on the B leg, the earth will feed round the A leg. Relay E on operating releases relay EP which re-makes the loop circuit thereby re-energising the gong, punch 40 register and the line relays.

The second two codes transmitted from the box are thus translated from earth pulses into loop pulses by relay EP and are correctly received on the punch register and gong, the first code transmitted being lost in order to discriminate between a genuine call and momentary earth leakages on the line.

At the conclusion of the code sending, relay E restores and maintains relay EP operated thereby breaking the loop circuit. Since no further pulses are received on the punch register, after a further short delay period provided mechanically thereon, this restores to normal and momentarily closes a pair of contacts *pr* to operate relay RR, which at armatures *rr1* and *rr2* releases the relays SX, M—S and J. Relay SX on releasing releases relay EP the loop circuit is thus re-made in readiness for further calls. Relay SX when it operated initially energized relay SCB which remains locked over its lower winding and thus maintains the short-circuited box call lamp SBL lighted until the cancel key KSCR is operated by the station attendant.

In the case of an earth fault on the line, relay E remains steadily operated and brings up relays ER and J in turn. Relay J completes a circuit for the delay relay EA and since relay PA is not now operated if the fault persists for twelve seconds or more relay EA operates and operates relay EF. Relay EF locks up to the

earth fault key EFK and lights the earth fault lamp EFL at armature $e/2$. In the case of one or two momentary earth leakages on the line which may be followed by continuous earth, a number of the impulse train counting relays M-S may be operated and locked, but these relays will be released at armature $e/3$ when relay EF is operated.

It will be understood that this latter method of short-circuited box working is applicable to both sector and succession box systems without modification in principle while furthermore it may be operated in conjunction with either manual or automatic changeover arrangements to earth working on a line break.

We claim:

1. In a fire alarm system, a call point and a central station, two conductors connecting said call point to said central station, said conductors normally connected together at said call point, means at said call point for repeatedly interrupting the connection between said conductors during the sending of a code to said central station, means for grounding said conductors at the call point whenever they are connected together during the sending of a code, said ground being disconnected from both conductors whenever said conductors are disconnected from one another during the sending of a code, a source of current at said central station normally connected between said two conductors to cause current to flow over said conductors in series when they are connected together at said call point, means at said central station responsive to interruptions of the current flow over said conductors in series, means operated at times to disconnect one of said conductors from said source at said central station and to connect it to the other conductor, said last means also effective at said times to ground said source thereby to cause current to flow from said source over said two conductors in parallel whenever said conductors are grounded at said call point, said third means then responsive to the interruptions of current flow over said two conductors in parallel whenever the ground is disconnected from said conductors at said call point.

2. In a fire alarm system, a call point and a central station, two conductors connecting said call point to said central station, said conductors normally connected together at said call point, means at said call point for repeatedly interrupting the connection between said conductors during the sending of a code to said central station, means for grounding said conductors at the call point whenever they are connected together during the sending of a code, said ground being disconnected from both conductors whenever said conductors are disconnected from one another during the sending of a code, a source of current at said central station normally connected between said two conductors to cause current to flow over said conductors in series when they are connected together at said call point, means at said central station responsive to interruptions of the current flow over said conductors in series, other means at the central station operated responsive to the first disconnection of ground from said conductors at said call point during the sending of a code, means operated conjointly by said last means and said third means to disconnect one of said conductors from said source at said central station and to connect it to the other of said conductors if said third means does not operate

responsive to the first disconnection of said conductors from one another during the sending of a code, said last means also effective, upon operation, to ground said source thereby to cause current to flow from said source over said two conductors in parallel whenever said conductors are grounded at said call point, said third means then responsive to the interruptions of current flow over said two conductors in parallel whenever the ground is disconnected from said conductors at said call point.

3. In a fire alarm system, a call point and a central station connected together by two conductors, a device at the central station for responding to electrical impulses transmitted from said call point during the sending of an alarm therefrom, said responding device normally connected in a circuit including said two conductors in series and operated responsive to impulses transmitted over said two conductors in series during the sending of an alarm from said call point, and means operated whenever said call point is short-circuited during the sending of an alarm to change the connections of said responding device to said conductors to render it responsive to impulses transmitted over said two conductors in parallel.

4. In a fire alarm system as claimed in claim 3, wherein the sending of an alarm from said call point is initiated by grounding said conductors at the call point, means at the central station operative responsive to a ground on said conductors to determine whether said ground is due to the initiation of an alarm or to a fault.

5. In a fire alarm system as claimed in claim 3, wherein the sending of an alarm from said call point is initiated by connecting ground through a rectifier to both of said conductors at said call point, means at said central station for determining whether a ground on said conductors is due to the initiation of an alarm or to a fault, said means including a source of direct current at said central station connected across said conductors, a test device for each of said conductors, and means for grounding each of said conductors at said central station through its respective test device, both of said test devices being operated if the ground on said line is due to a fault, said rectifier preventing one of said test devices from operating if the ground on said line is due to the initiation of an alarm.

6. In a central fire alarm station, two conductors incoming from a call box circuit, a responding device normally connected in a circuit including said two conductors in series and responsive to electrical impulses transmitted over said two conductors in series, and means operated at times for changing the connections of said device to said two conductors, said means effective to ground said device thereby to render it responsive to electrical impulses transmitted over said two conductors in parallel at said times.

7. In a fire alarm system, a call point connected to a central station by a metallic loop circuit, means at said call point normally operated to repeatedly interrupt said loop circuit during the sending of an alarm from said call point, thereby to transmit impulses over the two sides of said circuit in series, a responding device normally connected in series in said loop circuit and operated by said impulses, means at said call point effective during the sending of an alarm therefrom if said call point is short-circuited to transmit impulses over the two sides

of said circuit in parallel, and means operated if an alarm is sent from said call point while same is short-circuited to change the connections of said responding device to said circuit to cause it to respond to said impulses transmitted over the two sides of said circuit in parallel.

8. In a fire alarm system, a call point connected to a central station by a metallic loop circuit, a source of current in said loop circuit, a ground connection to said loop circuit at the call point, means at the call point for repeatedly interrupting said loop circuit during the sending of an alarm from said call point, said means effective also to disconnect said ground from at least one side of said loop circuit each time said loop circuit is interrupted, an ungrounded responding device at said central station connected in series in said loop circuit and normally operated over the metallic loop circuit exclusively responsive to each interruption of said loop circuit by said first means, a grounded responding device at said central station connected to said one side of the loop circuit and operated responsive to the first disconnection of ground from said one side by said first means upon initiation of the sending of an alarm from said call point, and means controlled conjointly by said two responding devices if said first device fails to operate concurrently with said operation of said second device to ground said first device, thereby to cause said first device to respond to the repeated disconnections of said ground from said one side of said loop circuit by said first means.

9. In a fire alarm system, a call point connected to a central station by a metallic loop circuit, a source of current in said loop circuit, a ground connection to said loop circuit at the call point, means at the call point for repeatedly interrupting said loop circuit during the sending of an alarm from said call point, said means effective also to disconnect said ground from at least one side of said loop circuit each time said loop circuit is interrupted, an ungrounded responding device at said central station connected in series in said loop circuit and normally operated over the metallic loop circuit exclusively responsive to each interruption of said loop circuit by said first means, a grounded responding device at said central station connected to said one side of the loop circuit and at times operated responsive to each disconnection of ground from said one side by said first means, and means controlled by said last responding device at said

times to interrupt said loop circuit at said central station upon each operation of said last device, thereby to insure the operation of said first responding device.

- 5 10. In a fire alarm system, a call point connected to a central station by a metallic loop circuit, a source of current in said loop circuit, a ground connection to said loop circuit at the call point, means at the call point for repeatedly interrupting said loop circuit during the sending of an alarm from said call point, said means effective also to disconnect said ground from at least one side of said loop circuit each time said loop circuit is interrupted, an ungrounded responding device at said central station connected in series in said loop circuit and normally operated over the metallic loop circuit exclusively responsive to each interruption of said loop circuit by said first means, a grounded responding device at said central station connected to said one side of the loop circuit and operated responsive to each disconnection of ground from said one side by said first means during the sending of an alarm from said call point if said call point is short circuited, means controlled by said grounded responding device to determine whether said operation of said grounded responding device is occasioned by the sending of an alarm from said call point or by a fault on said 20 loop circuit, and means controlled by said grounded responding device if said last means determines that said operation of the grounded responding device is occasioned by the sending of an alarm from said call point to interrupt said 25 loop circuit at said central station upon each operation of said grounded responding device, thereby to operate said ungrounded responding device despite the short circuit at said call point.
11. A fire alarm system as claimed in claim 40 10, wherein said first means is operated during the sending of an alarm to repeatedly transmit a predetermined code, and wherein said determining means includes a counting relay chain operated in the accordance with the first transmission of said code when an alarm is sent from said call point while said call point is short circuited, thereby to distinguish operation of said grounded responding device due to the sending of an alarm from operation of said grounded device due to a fault in the loop circuit.
